UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

LOOPER-ACTUATING MECHANISM FOR SEWING-MACHINES.

1,283,478.

Specification of Letters Patent.

Patented Nov. 5, 1918.

Original application filed March 21, 1916, Serial No. 85,535. Divided and this application filed April 5, 1917. Serial No. 159,887.

To all whom it may concern:

Be it known that I, ALBERT H. DE VOE, a citizen of the United States, residing at Westfield, in the county of Union and State 5 of New Jersey, have invented certain new and useful Improvements in Looper-Actuating Mechanisms for Sewing-Machines, of which the following is a specification, reference being had therein to the accompanying 10 drawings.

This invention relates to chain-stitch sewing machines, more particularly of the cylinder-bed type, and has for an object to provide a simplified and wear-resisting looper- 15 actuating mechanism, for machines of the type referred to, which shall comprise but few operative parts so connected as to operate quietly and efficiently at high speed.

To these ends, the looper-actuating mechanism may be embodied in a sewing machine frame having a transversely extending body-portion, within which the main-shaft is housed, and a downwardly and horizontally extending, hollow, L-shaped, work-supporting arm whose free end terminates beneath an overhanging head supported by a bracket-arm joined to the body-portion of the frame. In the present instance, the looper is housed within the free end-portion of the work- 20 supporting arm and is supported by a looper-carrier which is adjustably clamped about one end of a looper-supporting shaft journaled within and lengthwise of the work-supporting arm for rocking and sliding movements. The opposite end of the looper-shaft carries a crank-arm which is freely connected to the lower end of a looper-actuating lever whose upper end is strapped to embrace a spherically surfaced 25 eccentric on the main-shaft. The looper-actuating lever is connected between its ends to the horizontal portion of the work-supporting arm by means of a single movable member or anchor-link which is disposed 30 substantially in the plane of action of the looper-actuating link or, in other words, is disposed in a plane substantially parallel to the vertical plane through the looper-shaft. The anchor-link, in effect, affords a movable 35 fulcrum for said looper-actuating lever. The stresses imposed upon the anchor-link are of tension and compression only, as distinguished from bending stresses, and the use of a single anchor-link, in lieu of a more

elaborate system of connections with the 55 frame, makes for simplicity, durability, and freedom from lost motion.

In the accompanying drawings, Figure 1 is a side elevation of a machine-head of the feed-off-the-arm type showing the work-arm in section to reveal the looper mechanism housed therein. Fig. 2 is an end elevation. Fig. 3 is a cross-section through the machine in a vertical plane parallel with the main-shaft. Fig. 4 is a side elevation 65 of the looper-actuating mechanism alone, and Figs. 5 and 6 are detail views.

The invention, in its preferred embodiment, is incorporated in a sewing machine having a frame comprising a body-portion 70 1 which is adapted to be supported in the manner disclosed in my copending application, Serial No. 85,535, filed March 21, 1916, of which this application is a division, and at its opposite ends is provided with bearings 2 and 3 for the main-shaft 4 one end of which is extended beyond the frame and carries a hand-wheel 5. The main-shaft 4 is driven by means of the pulley-wheel 6 and carries various driving elements among 75 80 which is included the spherically surfaced looper-actuating eccentric 7.

Extending downwardly and rearwardly from the body-portion 1 is a hollow L-shaped work-arm 8 comprising a substantially vertical portion 9 and a substantially horizontal portion 10 supporting a throat-plate 11. Disposed directly above the free end of the work-arm 8 is the head 12 having a laterally projecting boss 13 connected to 85 the body-portion 1 by a channeled bracket-arm 14 disposed above and at one side of the work-arm 8 as shown in Fig. 2.

In the present instance, the machine is fitted with a pair of needles 15 which are 90 arranged in a plane inclined to the direction of feed and are supported by the needle-bar 16 which is reciprocated in the bearing bushings 17 carried by the head 12. A split collar 18 surrounds the needle-bar 16 and is 95 clamped thereon by a screw 19. This collar carries a pin 20 embraced by the lower end of a link 21 whose upper end embraces a crank-pin 22 projecting from the flat face 23 of the bevel-gear 24 mounted on one end 100 of a short shaft 25 journaled in the bearing boss 13. A collar 26 co-operates with the bevel-gear 24 to hold the shaft 25 in place. 105

Meshing with the bevel-gear 24 is a similar gear 27 carried by one end of the downwardly inclined shaft 28 journaled in the bearings 29 and 30. The lower end of the shaft 28 projects into the hollow housing or body portion 1 and carries a bevel-gear 31 which meshes with a driving gear 32 secured to the main-shaft 4.

A presser-foot 33 is pivoted at 34 to a shank 35 carried by the presser-bar 36 mounted behind the needle-bar 16 in the head 12. The usual spring 37 and lifting lever 38 are employed to lower and raise the presser-foot.

Coöoperating with the needles 15 are two thread-carrying loopers 40 secured to a looper-support 41 adjustably clamped on one end of the rocking and endwise movable looper-shaft 42 extending within and lengthwise of the horizontal portion 10 of the work-arm. Adjustably clamped around the other end of looper-shaft 42 is a split-collar 43 carrying a crank-arm 44 having a ball end-portion 45 received in a socket in the lower end-portion 46 of a looper-actuating lever whose upper end-portion 47 embraces the spherically surfaced driving eccentric 7 on the main-shaft. The lower end-portion 46 of the looper-actuating lever is threaded at 48 and screwed into a correspondingly threaded opening in the upper portion 47 to which it is securely held by a lock-nut 49. A ball 50 formed on the lower portion 46 of the looper-actuating lever is connected by a link 51 to another ball element 52 formed between the ends of a pin 53 extending horizontally across the end of the horizontal section 10 of the work-arm 8 and fitted tightly in holes therein as shown in Fig. 3. The link 51 is strapped at its opposite ends to embrace the ball-elements 50 and 52, respectively. It will be seen that the driving eccentric 7 will raise and lower the looper-actuating lever 46, 47 causing it to rock the looper-shaft 42 and impart loop-taking and loop-shedding movements to the loopers. At the same time the eccentric 7 will rock the lever 46, 47 about the ball-and-socket connection with the anchor-link 51 as a fulcrum and thereby impart side-wise or needle-avoiding movements to the loopers. The actuating mechanism between the eccentric ball 7 and the looper-shaft 42 is seen to be devoid of slidable connections and comprises but four working joints. The simple link 51 is used to connect the fulcrum ball 50 with the fixed ball 52 and, since the lever 46, 47 and link 51 operate substantially in a plane parallel to the looper-shaft 42, it is obvious that the link is subjected to lengthwise stresses only, due to the reaction of the lever 46, 47. By adjusting the length of the lever 46, 47 the position of the ball 50 relatively to the eccentric 7 and fixed ball 52 may be altered, thus changing the shape and

position of the path of the ball 45 and consequently varying the path of movement of the loopers. To prevent accidental turning movement of the lever 46, 47, the lower end thereof is provided with two laterally projecting spaced lugs 54, which embrace a headed portion 55 projecting from the ball 45, and connected thereto by a reduced neck 56 as shown in Fig. 6.

While I have shown and described the preferred embodiment of the invention it is to be understood that the form and arrangement of the various parts are susceptible of material modification within the scope of the invention as defined in the appended claims. The looper-actuating lever need not necessarily have its fulcrum point between its ends, as in the embodiment illustrated, but may be a lever of any of the three known types.

Having thus set forth the nature of the invention, what I claim herein is:—

1. Looper operating mechanism for sewing machines comprising, a frame, a main-shaft, a looper mounted for loop-taking and needle-avoiding movements, and driving connections between said main-shaft and looper including a rocking and endwise movable lever pivotally connected at one point along its length with said looper, and a link connected at one end to another point along the length of said lever and at the other end to a stationary part of the machine, whereby a movable fulcrum for said lever is provided.

2. Looper operating mechanism for sewing machines comprising, a main-shaft, a looper, a looper-supporting shaft mounted for rocking and endwise sliding movements, a crank-arm on said shaft, a rocking and endwise movable lever connected at one point in its length to said crank-arm and at another point to said main-shaft, and a link connected at one end to a third point in the length of said lever and at the other end to a stationary part of the machine, whereby a movable fulcrum for said lever is provided.

3. Looper operating mechanism for sewing machines comprising, a main-shaft, a looper, a looper-supporting shaft mounted transversely of the main-shaft for rocking and endwise sliding movements, and actuating connections between said shafts including a rocking and endwise movable lever, a link connected at one end to said lever and at the other end to a fixed part of the machine, the plane of said lever and link lying substantially parallel to the looper-supporting shaft, whereby the reaction of said lever is transmitted directly along said link to said fixed part of the machine.

4. In a sewing machine, in combination, a frame having a hollow body-portion and a downwardly and horizontally extending

L-shaped, hollow work-arm, a main-shaft extending in a direction transverse of the work-arm, and looper operating mechanism housed within said work-arm and comprising a looper, a looper-supporting shaft journaled within and lengthwise of the horizontally extending portion of the work-arm, a crank-arm on said looper-supporting shaft, a connection including a rocking and endwise movable lever between said crank-arm and said main-shaft, and a link connected at one end to said lever and fixed at its opposite end within the horizontally extending portion of the work-arm.

5 5. Looper operating mechanism for sew-

ing machines comprising, a frame, a looper, a looper-supporting shaft journaled in said frame for rocking and endwise movements, a crank-arm on said looper-supporting shaft, a main-shaft extending transversely of said 20 looper supporting shaft, an eccentric driving element on said main-shaft, a lever connecting said eccentric driving element with said crank-arm, and a link connected at one end to said lever at a point spaced from said 25 driving element and crank-arm and at its opposite end anchored to the frame.

In testimony whereof, I have signed my name to this specification.

ALBERT H. DE VOE.
